UNITED STATES PATENT OFFICE

GEORGE A. HOLMES, OF NEWTON, MASSACHUSETTS, ASSIGNOR, BY MESNE ASSIGNMENTS, TO UNITED-CARR FASTENER CORPORATION, OF CAMBRIDGE, MASSACHUSETTS, A CORPORATION OF MASSACHUSETTS

FASTENER PLATE

Application filed December 13, 1927. Serial No. 239,678.

This invention relates to snap fasteners of the type much used, for example, on automobile curtains and the like.

The invention aims to improve the construction of the back plates of fasteners of this general type with a view to facilitating the handling of such plates in machines for automatically setting the fasteners.

The nature of the invention will be readily understood from the following description when read in connection with the accompanying drawings, and the novel features will be particularly pointed out in the appended claims.

15 In the drawings,

Figure 1 is a perspective view showing the socket member and back plate, respectively, of a common type of snap fastener;

Fig. 2 is a cross-sectional view, partly in elevation, showing the manner in which these back plates frequently jam in a raceway;

Fig. 3 is a perspective view of a blank of the form which preferably is used in the manufacture of my back plate;

25 Figs. 4 and 5 are perspective views showing, respectively, the upper and lower sides of a back plate embodying this invention; and

30 Fig. 6 is a vertical cross-sectional view through the socket member, shown in Fig. 1.

A fastener of the general type above referred to comprises a stud (not shown) and a socket member 2 which is provided with 35 springs or spring pressed parts for yieldingly gripping said stud. This socket member is secured to a curtain, or the like, by means of prongs 3 which are forced through the material of the curtain and enter slots 4 in a 40 back plate 5, the prongs being clinched over upon this back plate. The socket 2 also is made up of members which are secured together by clinched prongs 6 as shown in Fig. 1. In order to accommodate the latter 45 prongs, small recesses are punched in the

lower surface of the back plate 5, thus forming lugs 7.

In making a raceway for these back plates it is necessary to allow considerable vertical clearance for the plates in order to permit 50 them to travel freely and also to accommodate the short burrs which sometimes are formed on the plates in the process of manufacture. As the plates run down the raceway it occasionally happens that they become 55 jammed together, thus interrupting the setting operation and requiring the release of the jammed parts. This action is caused by the adjacent edges of the plates riding one upon the other in some such relationship as 60 that shown, for example, between the plates 5' and 5" in Fig. 2. The surfaces of the lugs 7 adjacent to the edges of the plates are bevelled, as clearly shown in Fig. 1, and this bevelled construction facilitates the overriding 65 of one plate upon the other and the consequent jamming of both plates in the raceway.

I have overcome this difficulty by providing a construction such as that shown in Figs. 70 4 and 5 in which the back plate 8 is constructed like the plate 5 except that the lugs 9 at opposite ends of the plate, instead of being made like the lugs 7, are provided with 75 very abrupt end faces or shoulders on the sides thereof toward the respective ends of the plate. Preferably each lug has an end face 10 which is located substantially flush with the edge of the plate at one end thereof, and these lugs project for a considerable distance above the upper surface of the plate. Each lug also is relatively wide where it joins the edge of the plate and is provided with a narrower part which extends backwardly away from said edge. This construction thus provides a back plate in which the overall thickness of a portion of the edge at each end is increased very substantially and this thickened portion preferably is considerably wider than the ordinary lug. 80 85 90 95

When such plates are fed down a raceway end to end the relatively thick end faces 10—10 effectually prevent any tendency of one plate to slide over or under the next adjacent plate so that any jamming of the plates in the raceway from the cause above described is prevented. Often the raceways in which such plates are fed are curved so that one plate is offset somewhat with reference to the next adjacent plate as it travels around the curve. By making the thickened faces 10—10 relatively wide the lugs still prevent any tendency of one plate to override another, even in this offset relationship. It will be observed that the back plate is, roughly speaking, of oval shape, or stated more accurately, has straight sides and rounded ends. These straight sides are useful in guiding the plates through the delivery chute.

While the plate 8 can be manufactured in any convenient way or shape (it being shown as round in Fig. 1 and longer than it is wide in Figs. 4 and 5), it is preferable to make it by a pressed metal process, a blank being cut out of suitable stock and this blank subsequently shaped to the desired form. Fig. 3 shows at 8' a blank suitable for this purpose but before it has been stamped. When this method is used I prefer to make the blank with very short projections or ears 9'—9' at opposite ends in order to provide ample stock with which to make a shoulder 10, Fig. 4, of the desired height at the end of each lug 9. The finished fastener plate is provided with the usual slots 4" to receive the prongs 3 of the socket member 2. Side lugs 7" corresponding to the lugs 7, Fig. 1, are also pressed in the metal of the plate to form cavities adapted to receive the tips of two of the prongs 6, the tips of the other two prongs 6 being accommodated in the cavities formed in the end lugs 9—9.

While I have herein shown and described a preferred embodiment of my invention, it will be understood that the invention may be embodied in other forms without departing from the spirit or scope thereof.

Having thus described my invention, what I desire to claim as new is:

1. A back plate for snap fasteners having a portion of its edge thickened substantially for a short distance only to provide means for abutment against another like plate to prevent overlapping of the plates when being fed along a chute in a fastener-attaching machine and provided with apertures to receive the prongs of a cooperating fastener member.

2. A back plate forming part of a socket member of a snap fastener, said back plate having a thickened portion presenting an abrupt shoulder at one end thereof for a short distance only along the edge to provide means for abutment against another like plate to prevent overlapping of the plates

when being fed along a chute in a fastener-attaching machine, and having cavities pressed in the material of the plate to receive projecting parts of another part of said socket member.

3. A back plate for snap fasteners having a lug projecting from one face thereof near one end of the plate to receive a clenched prong of a cooperating fastener member, said lug having a wide portion located substantially at the edge of the plate and a narrower portion located at a distance inwardly from said edge, the wide portion of said lug having an abrupt shoulder projecting substantially above the face of the plate and located approximately at the end of the plate to provide means for abutment against another like plate to prevent overlapping of the plates when being fed along a chute in a fastener-attaching machine.

4. A back plate for snap fasteners having lugs projecting from one face thereof near opposite ends of said plate to receive a clenched prong of a cooperating fastener member, each of said lugs having a wide portion provided with an abrupt shoulder located approximately at the edge of the plate and projecting a substantial distance above the surface of the plate to provide means for abutment against another like plate to prevent overlapping of the plates when being fed along a chute in a fastener-attaching machine, each lug also including a narrower portion extending inwardly away from said edge.

5. A back plate for snap fasteners having a lug projecting from one face thereof near one end of said plate, said lug having an abrupt shoulder projecting substantially above the surface of the plate and located adjacent to the edge of the plate to provide means for abutment against another like plate to prevent overlapping of the plates when being fed along a chute in a fastener-attaching machine, and additional lugs pressed from the material of the plate and forming cavities in the plate to receive projecting parts of a cooperating fastener member.

6. A back plate for snap fasteners, said plate being of greater length than width and having rounded ends and straight portions on each of its sides, and lugs formed on the opposite end portions of said plate and presenting abrupt shoulders at said opposite rounded ends serving to increase the overall thickness of the plate at said ends for a short distance only to provide means for abutment against another like plate to prevent overlapping of the plates when being fed along a chute in a fastener-attaching machine, said plate having apertures therethrough to receive the prongs of a cooperating fastener member.

7. A back plate for a snap fastener having

a lug projecting from one face thereof near the outer edge of the plate for a short distance only, said lug having an abrupt shoulder projecting substantially above the surface of the plate and located adjacent to the edge of the plate to provide means for abutment against another like plate to prevent overlapping of the plates when being fed along a chute in a fastener attaching machine and said plate having attaching means for cooperative engagement with attaching means of a cooperating fastener part.
